VISUAL SIGNAL CALL SYSTEM

John H. Wheelock, Fitzwilliam, N. H., assignor to
 Signal Engineering & Manufacturing Company,
 New York, N. Y., a corporation of Massachusetts

Application December 5, 1929, Serial No. 411,764
 Renewed August 15, 1934

8 Claims. (Cl. 177—380)

The present invention relates to signal call systems and has for its object to provide a visual call system that is adapted to clearly display selected signals. Such a system is particularly adapted for use in hospitals, or other places where it is not desirable or practicable to have signals sounded; the display of cab calls or the display of stolen automobile numbers being within the capabilities of the system.

According to the present invention there are distributed throughout the system a desired number of visual call boards, each one of which is adapted to intermittently display a signal or signals selected by an operator, usually located at a telephone switch board, who can also cause several designated signals to be displayed in sequence. Thus when the system is installed in a hospital, for example, it is possible to successively display the numbers of several physicians who may be located in different parts of the building. The above and other advantageous features of the present invention will hereinafter more fully appear, reference being had to the accompanying drawings, in which,—

Fig. 1 is a diagrammatic view illustrating the arrangement of the apparatus entering into the present invention.

Fig. 2 is a horizontal sectional view of one of the signal code setting units.

Fig. 3 is a fragmentary view illustrating the operation of the selector mechanism.

Fig. 4 is a diagrammatic view of the whole system illustrating the display of a designated signal call at the stations.

Like reference characters refer to like parts in the different figures.

Referring first to Figs. 1 and 4, the system generally consists of a code setter generally designated by the reference character A preferably located near a telephone switch board where it is convenient to the operator. The code setter A consists of a number of similar units 10, 10', 10'', each providing a series of operating keys designated 1 to 9 inclusive, the operation of which will be hereinafter described. The several units 10 are connected by a multiple conductor cable 11 to a number of relay devices 12 which are adapted to control the energization of signal display boards B distributed at points where they may be readily observed, each board B providing a number of lamps 13 bearing numbers corresponding in sequence to the numbers of keys 1 to 9 inclusive in each unit 10 of the code setter A. Each series of lamps 13 is so controlled by its relay 12 that when illuminated, a number will be dis-

played at all the boards B corresponding to the number of a depressed key.

The system is adapted to be operated from a suitable source of electrical energy indicated at 14 to the — side of which the code setting units 10 and the signal relays 12 are connected through a common conductor 15. The + side of the source 14 is adapted to supply energy to a current interrupting device 16 which is adapted to automatically make and break a circuit leading to a selector 17 having a rotatably mounted contact arm 18 adapted to successively engage groups of contacts 19, 19', 19'' corresponding in number to the number of units 10, 10', 10'' etc., of the code setter A. A suitable operator's switch 20 is provided in the circuit between the + side of the source 14 and the signal sender 16 which when closed is adapted to connect the interrupter 16 and the selector 17 to the source 14, the entire system being deenergized when the switch 20 is open.

Referring now to Figs. 2 and 4, one of the code setting units 10 is shown in detail, and since all of the units are identical in construction, only one need be described. The keys 1 to 9 inclusive of a unit 10 each provide a shank 21 slidably mounted in the front 22 of the box which encloses the unit, each shank 21 being surrounded by a spring 23 which tends to hold the key in a forward or inoperative position. Each key carries a pair of resilient contact fingers 24 and 25 connected together but insulated from the key, each finger 24 being always in engagement with a bus bar 1a, 2a or 3a, etc., as the case may be, corresponding to the number of the key on which the finger 24 is mounted. Thus there are nine bus bars numbered 1a to 9a inclusive all connected to the keys 1 to 9 inclusive and in sliding engagement therewith. As shown in Fig. 4, the bus bars 1a to 9a inclusive extend between the several units 10, 10' and 10'', so that the several keys designated 1 of the several units 10 are always connected to the bus bars 1a. Furthermore, the bus bars 1a to 9a inclusive are connected to the corresponding number of conductors in the cable 11 and the conductor connected to the bus bar 1a is connected to one terminal of the winding 26 of a relay 12, one contact 27a of which is connected in parallel to all those lamps 13 of the signal boards 12 which when illuminated will show the numeral 1. The bus bars 2a, 3a, 4a etc. are similarly connected to conductors in the cable 11 leading to windings 26 of relays 12, the contacts 27a of which lead to the lamps 13 which when illuminated are adapted

to display the numerals 2-3-4, etc. The other terminals of all of the windings 26 are connected to the common conductor 15 leading to the - side of the source 14, as clearly shown in Fig. 4 as are also the contacts 27b of all the relays 12. The several series of lamps 13 are all connected in parallel on one side to the + side of source 14, so that when any relay 12 is closed by energization of its winding 26, the corresponding series of lamps will be illuminated by closing of the relay contacts 27a and 27b.

Referring again to Fig. 2, the finger 25 of each key extends rearwardly and when a key is depressed against the force of the spring 23, the finger 25 is moved out of alignment with the other fingers 25 into close proximity and parallel to a contact bar 28 extending along the rear of the unit, although out of contact therewith. When the key 1 is depressed as shown, it is locked in this position by a spring pressed latch 26a carried by a shiftable plate 29 through which the shank 21 passes, the latch plate 29 also carrying a series of latches 29a adapted to lock other keys such as 3 and 4 which are also shown as being depressed to bring their fingers 25 into parallel relation with the contact bar 28. The contact bar 28 is mounted on a pivot 28a at one end while its other end is opposed to a magnetic core 30a surrounded by a solenoid 30. The bar 28 is normally held out of engagement with the core 30a by means of a spring 31 which also serves to hold the bar 28 away from the fingers 25 of the several depressed keys 1, 3, and 4, as shown. One terminal of the solenoid 30 is connected to the common conductor 15 leading to the - side of the source 14 while the other terminal thereof is connected to the group of selector contacts designated 19 to which current from the + side of the source 14 is adapted to be supplied when the movable arm 18 engages any contact 19. Consequently, when the contact arm 18 engages a contact 19 energization of the solenoid 30 will cause the free end of the bar 28 to be attracted by the core 30a, thereby shifting the bar 28 about its pivot 28a, against the pull of the spring 31, to simultaneously engage all of the fingers 25 that are in the path of the bar by reason of the depression of the corresponding keys. This movement of the bar 28 will also cause its free end to engage a contact 30b connected to the selector contact 19, thereby energizing all of the fingers 25 engaged by the bar 28.

When the fingers 25 on the keys 1, 3, and 4 are so engaged by the energized bar 28, the bus bars 1a, 3a, and 4a are simultaneously energized to close the corresponding relays 12 and lamps 13 bearing the numbers 1, 3, and 4 will be simultaneously illuminated in all of the signal boards 12 to display the signal "1-3-4" throughout the system. Obviously, the designated lamps will remain illuminated so long as the selector arm 18 remains in engagement with any selector contact 19 and the functioning of the signal sending device 16 whereby the selector arm 18 will intermittently engage the contacts 19 will next be described.

As shown in Fig. 3, the selector arm 18 is carried by a shaft 32 carrying a ratchet wheel 33. The angular displacement between the teeth 34 of the ratchet wheel 33 is such that turning the shaft 32 through the displacement of one tooth 34 moves the arm 18 from one contact 19 to the next contact 19' of any group. An arm 35 carrying a pawl 36 is pivoted on the shaft

32 and the arm 35 is connected by a link 37 to the pivoted armature 38 of a solenoid 39 which when energized is adapted to cause turning of the wheel 33 by the pawl 36 through the displacement of one tooth 34. The armature 38 is also adapted to connect the selector 18 to the + side of the source 14 by bridging stationary contacts 40, shown in Fig. 4, energization of the solenoid 39 being under the control of the current interrupting device 16 as will now be 10 described.

One terminal of solenoid 39 is connected to the - side of source 14 while its other terminal is connected to a stationary contact 41 of the sender 16. The sender 16 provides a filament 42 passing several times around pulleys, freely rotatable, and has one end connected to an anchor post 43 that is in turn electrically connected to the + side of the source 14 when the switch 20 is closed. When the filament 42 is at ordinary room temperature, it exerts a pull on a pivoted switch arm 44 so as to hold the free end of a spring contact 45 carried by the arm 44 in engagement with the stationary contact 41 leading to the solenoid 39. Let it now be assumed that the switch 20 is closed by the telephone operator who has previously depressed keys 1, 3, and 4 so as to display the call signal "1-3-4" upon operation of the mechanism. Upon closing the switch 20, current flows from the + side of the source 14 through the filament 42, to the arm 44 through contacts 45 and 41 and from thence through the solenoid 39. Energization of solenoid 39 will cause the armature 38 to first move the selector arm 18 into engagement with contact 19, as shown in dotted lines, and then bridge contacts 40 to energize solenoid 30. This will shift the bar 28 into engagement with the fingers 25 on the depressed keys 1, 3, and 4, thereby illuminating the lamps 13 at all the boards 12 to show the signal "1-3-4". As current continues to flow through the filament 42, with the signal lamps energized, it will expand and permit a spring 44a acting on arm 44 to turn the arm 44 clockwise and cause separation of the contacts 41 and 45 after the signal lamps 13 have been illuminated a predetermined length of time.

In order to separate contact 45 from stationary contact 41 with a quick movement, there is preferably employed a throw over device of the type 50 shown in a copending application, Serial No. 291,441, filed July 9, 1928 by Charles L. Hanel, Patent No. 1,868,500 dated July 26, 1932, and assigned to the Signal Engineering & Manufacturing Company. As fully shown and described in the aforesaid copending application, the movable contact 45 is composed of resilient material having its central portion cut away to provide spaced fingers 45a with a tongue 46 therebetween, the fingers 45a and the tongue 46 being joined together only adjacent to the contact 41 opposite to the points of attachment of the fingers 45a to the arm 44 by the screws 47. The tongue 46 is bent into a double loop, shown at 48, near its juncture with contact 45, the free end of the tongue 46 extending in the direction of the arm 44 where it is received in a notch 49 provided in the end of the arm 44. With the parts in the position shown in Fig. 3, the end of the tongue 46 is disposed considerably below the resilient fingers 45a, so that the tongue 46 exerts an upward thrust tending to maintain the contact 45 in engagement with the stationary contact 41 that is connected to the solenoid 39 and the contacts 45 and 41 are thus maintained in engage- 75

ment so long as a pull is exerted on the arm 44 by the cold filament 42.

When the switch 20 is closed, current flowing through the filament 41 causes it to expand as it heats up, thus permitting the spring 44a to turn the arm 44 in a clockwise direction about its axis. As the arm 44 is thus moved upwardly with respect to the contact 41, the end of the tongue 46 in the notch 49 crosses a line joining the free end of the fingers 45a with their points of attachment to the rigid arm 44, whereupon the tongue 46 exerts a thrust tending to separate contact 45 from the contact 41 with a quick movement thereby deenergizing solenoid 39 and breaking the control circuit for the lamps then illuminated as the falling armature 38 separates contacts 40. In other words, the armature 38 breaks all of the lamp relay circuits and limits arcing to the contacts 40 which can be sufficiently heavy for the currents handled. Since current is no longer flowing through the filament 42, the latter cools and as it contracts, it turns the arm 44 in a counterclockwise direction and swings the notch 49 downwardly until the thrust of the tongue 46 snaps the contact 45 back into engagement with the stationary contact 41. When this occurs, the circuit through the solenoid 39 is reestablished, the armature 38 turns the selector arm 18 to engage contact 19', and the solenoid 30' is energized, thereby drawing down the contact bar 28' so as to engage whatever fingers 25 are presented to the bar by the depression of keys of the second unit 10'. In Fig. 4, the keys numbered 2, 4, and 5 are depressed and since the selector arm 18 is engaged with the second selector contact 19', the lamps at the signal boards B will be illuminated to show the signal "2-4-5". The particular construction of the stepping mechanism represented by the armature 38 and its linkage to the ratchet wheel 34 is more fully shown and described in my copending application Serial No. 417,469, filed Dec. 30, 1929, jointly with Charles L. Hanel.

After the signal "2-4-5" has been displayed a predetermined period, the filament 42 will again expand, thereby permitting the switch contact 45 to again leave contact 41 to extinguish the lamps by again deenergizing solenoid 39. After predetermined intervals, the arm 18 will be moved from the contact 19' to the contact 19'' and then from 19'' to contact 19''' and finally into reengagement with the second contact 19 of this group, whereupon the first signal "1-3-4" will again be shown.

Obviously the signals will continue to be displayed at the signal boards B so long as the keys of the several signal setting units remain depressed. However, as soon as any one answers in response to the showing of a given signal, the switch board operator can cause this signal to be omitted from the cycle by pushing the latch plate 29 of any particular unit from right to left, as viewed in Fig. 2, to release the depressed keys from the latches 29a. The release of the keys of a given setting unit will have no effect on the keys of the other units so that the other signals will continue to be shown as long as any keys remain depressed. After all the persons whose signals have been shown have answered the calls, all of the keys are released and the operator opens the switch 20 whereupon the arm 18 comes to rest in engagement with one of the contacts 19 to 19'''. Consequently, the operator can observe the position of the arm 18 and so determine which unit 10 will be first shown when the system is again placed

in operation by closing the switch 20. Obviously the cycle of operations described above will continue indefinitely so long as the switch 20 remains closed and the keys of any one of the signal setting units 10 are depressed.

From the foregoing, it is apparent that by the present invention there is provided an automatically operated signal system that is adapted to display visually, certain selected signals, any given signal being shown a predetermined interval after which it is automatically extinguished and another different signal displayed if desired. Due to the cycle of operation employed, it is possible to display several different signal numbers independently of the others so that several persons can be called at one time. This flexibility in operation is believed to render the present system much more effective than signal systems of the type heretofore employed in which it has been possible to sound only one signal at a time. By the present system a given signal will continue to be shown until it is answered, although during this period several other different signals may be displayed and answered. By employing the switch arm 44 to make and break the signal energizing circuits, as well as the selector operating circuit, all arcing is restricted to the switch contacts 45 and 40.

In addition to the above described use of the system in a hospital to noiselessly call the attention of doctors, or other persons, it is equally well adapted for other uses. For example, it can readily be employed for police purposes to display at certain designated points, on main traffic arteries, the numbers of stolen automobiles or the numbers of vehicles involved in crimes. The system can also be employed for calling cab numbers at theatres or other public places. In other words, the invention can be used advantageously in any electrical system in which it is desired to establish the flow of current in different multiples of branch circuits, in a given sequence.

I claim,

1. In a signal system, a code determining device comprising a plurality of sets of key operated contact members, each of which is individually movable from a retracted position to an advanced code determining position, a plurality of common movable contact members, one for each set of keys, for simultaneously engaging the advanced contact members of each set, parallel electrical connections extending between corresponding contact members of the different sets, and means for sequentially causing the movement, one at a time, of the common contact members to engaging position with the advanced contact members of the corresponding set.

2. In a signal system, a code determining device comprising a plurality of sets of key operated contact members, each of which is individually movable from a retracted position to an advanced code determining position, a plurality of common movable contact members, one for each set of keys, for simultaneously engaging the advanced contact members of each set, parallel electrical connections extending between corresponding contact members of the different sets, a series of electro-magnets for individually controlling the common contact members of the several sets, and means for sequentially energizing said electro-magnets to cause successive energizations of said electrical connections in accordance with the arrangement of the depressed contact members of each set.

3. In a signal system, a code determining device comprising a plurality of sets of key operated contact members, each of which is individually movable from a retracted position to an advanced code determining position, a plurality of common movable contact members, one for each set of keys, for simultaneously engaging the advanced contact members of each set, parallel electrical connections extending between corresponding contact members of the different sets, a series of electro-magnets for individually controlling the common contact members of the several sets, a series of spaced stationary contacts connected separately to said electro-magnets, and means for sequentially energizing said stationary contacts to cause sequential operation of the common contact members by said electro-magnets. 5
4. In a signal system, a code determining device comprising sets of spaced contacts, individually operable from a non-code to a code determining position, movable bridging members, one for each set of contacts, for simultaneously engaging the operated contacts of each set, electrical connections extending between corresponding contacts of the different sets, and means for sequentially causing the movement, one at a time, of said bridging members to close all of the gaps between the contacts of each set that are in code determining position. 10
5. In a signal system, a source of electrical energy, a code determining device comprising sets of contacts, individually operable from a non-code to a code determining position, movable bridging members, one for each set of contacts, for simultaneously engaging the contacts of each set that have been moved to code determining position, electrical connections extending between corresponding contacts of the different sets, and means operated from said source for sequentially moving said bridging members to engage the operated contacts of each set to cause successive energizations of said electrical connections from said source in accordance with the different code determinations of the operated contacts. 15
6. A signal system, a source of electrical energy, a code determining device comprising sets of contacts individually operable from a non-code to a code determining position, electrical connections extending between corresponding contacts 20
- of the different sets and energized from one side of said source, movable bridging members, one for each set of contacts, for simultaneously engaging the operated contacts of a set, and means for sequentially moving said bridging members, when energized from the other side of said source, to cause the flow of current successively through said connections in accordance with the different code determinations of the operated contacts in the different sets. 25
7. A signal system, a source of electrical energy, a code determining device comprising sets of contacts individually operable from a non-code to a code determining position, electrical connections extending between corresponding contacts of the different sets and from one side of said source, movable bridging members, one for each set of contacts, for simultaneously engaging the operated contacts of a set, means for sequentially moving said bridging members, when energized from the other side of said source, to cause the flow of current through said connections in accordance with the different code determinations of the operated contacts in the different sets, and means operating between successive movements of said members for simultaneously breaking the circuits through all of said connections, independently of said bridging members and operated contacts. 30
8. A signal system, a source of electrical energy, a code determining device comprising sets of contacts individually operable from a non-code to a code determining position, electrical connections extending between corresponding contacts of the different sets and from one side of said source, movable bridging members, one for each set of contacts, for simultaneously engaging the operated contacts of a set, means for sequentially moving said bridging members, when energized from the other side of said source, to cause the flow of current through said connections in accordance with the different code determinations of the operated contacts in the different sets, and a pair of contacts connected to all of said bridging members for simultaneously breaking the circuits through all of said connections in the intervals between successive movements of said bridging members. 35

JOHN H. WHEELOCK.
